DESIGN FOR A PULL-CORD CLIP FOR WINDOW BLINDS OR THE LIKE

William M. Jones, Anderson, Ind.

Application May 19, 1939, Serial No. 85,087

Term of patent 7 years

To all whom it may concern:

Be it known that I, William M. Jones, a citizen of the United States, residing at Anderson, in the county of Madison and State of Indiana, have invented a new, original, and ornamental Design for a Pull-Cord Clip for Window Blinds or the like, of which the following is a specification, reference being had to the accompanying drawings forming part thereof.

In the drawing, Figure 1 is a front view, and

I claim:

The ornamental design for a pull-cord clip for window blinds or the like, as shown.

WILLIAM M. JONES.
